ADJUSTABLE PRESSER FOOT AND NEEDLE CLAMP

Filed Dec. 27, 1923

2 Sheets-Sheet 2

UNITED STATES PATENT OFFICE.

ABRAHAM BEBEL, OF NEW YORK, N. Y., ASSIGNOR TO THE DE LONG HOOK AND EYE COMPANY, OF PHILADELPHIA, PENNSYLVANIA, A CORPORATION OF PENNSYLVANIA.

ADJUSTABLE PRESSER FOOT AND NEEDLE CLAMP.

Application filed December 27, 1923. Serial No. 682,895.

This invention relates to an attachment for sewing machines intended for use in sewing hook and eye holding tapes upon brassières and other garments of wearing apparel, the present invention being a further development of one disclosed in Letters Patent of the United States No. 1,524,013, dated January 27, 1925.

In the said Letters Patent a sewing machine attachment is shown comprising means for supporting and guiding hook and eye tape of different widths in operative relation to the feeding and sewing mechanism of said sewing machine. The said guiding means comprising a couple of spaced guiding plates which are adjustable toward and from each other, the inner edges of which operate as guides for the opposite edges of the hook and eye tape.

The general object of the present invention is to provide a novel construction of means whereby the two presser feet and the two needles of the machines which are adapted for simultaneously stitching the opposite edges of hook and eye tape may be adjusted to adapt them for use in connection with the said attachment in the sewing of hook and eye tape of different widths.

For further comprehension of the invention, and of the objects and advantages thereof, reference will be had to the following description and accompanying drawing, and to the appended claims in which the various novel features are more particularly set forth.

Fig. 1 of the drawing is a perspective view of my improved attachment.

Fig. 2 is a rear view of the presser foot bracket.

Fig. 3 is a transverse sectional view on the line 3—3 of Fig. 2.

Fig. 4 is a front view of the presser foot bracket with the front plate removed.

Fig. 5 is a face view of the needle holder.

Fig. 6 is a transverse sectional view taken on the line 6—6 of Fig. 5.

Fig. 7 is a rear view showing a modified form of needle holder.

Fig. 8 is a longitudinal sectional view taken on the line 8—8 of Fig. 7.

Fig. 9 is a sectional plan view taken in the plane of lines 9—9 in Figs. 11 and 12 of a hook and eye tape supporting and guiding

device adapted to be attached to a sewing machine.

55

Fig. 10 is a similar view taken in the plane of lines 10—10 of Figs. 11 and 12.

Fig. 11 is a longitudinal central sectional view taken on the line 11—11 of Fig. 9.

60

Fig. 12 is a transverse sectional view taken on the line 12—12 of Fig. 10.

65

Fig. 13 is a transverse sectional view taken on the line 13—13 of Fig. 10.

70

In Figs. 1, and 9 to 13, inclusive, of the drawing I have shown the hook and eye tape supporting and guiding attachment by means of which the said tape is supported and guided through the machine in operative relation to the work feeding and sewing mechanism which is illustrated in Figs. 1

75

to 8 inclusive. The hook and eye tape supporting and guiding attachment comprises a base or bottom portion 10 and a top plate 10^a.

75

The bottom plate 10 comprises a main or body portion, as clearly indicated in Figs. 1, 9 and 10, which is of substantially rectangular shape, and from the forward edge of which projects a tongue-like portion 10^b, from the opposite edges of the forward end portion of which projections 10^c extend.

80

Bars 11 and 12 arranged in pairs as shown in the drawing are adjustably mounted upon the bottom plate 10.

75

The outer bars 12 are held in adjusted position by means of screws 12^a, the bottom end portions of which may be adjusted back and forth in slots 12^b.

80

The inner bars 11 are held in adjusted positions by means of screws 12^c, which may be adjusted back and forth in the slot 12^d.

85

Mounted upon the top sides of the opposite edge portions of the rectangular shaped portion of the base member 10 are bars 12^e which are of rectangular shape in cross section.

80

These bars are held in place by the screws 12^f. Tape guiding plates 12^g are mounted above the bars 12^e and underneath the opposite edge portions of the top plate 10^a of the attachment.

85

The inner edges of the plate 12^g are spaced from each other as clearly shown in Fig. 12 and are adjustable toward and from each other. The said plates 12^g are held in adjusted, clamped

90

position between the top plate 10^a and the bars 12^e by means of screws 12^h which extend through elongated transversely extending slots 12ⁱ in the said plates 12^g.

95

The inner edges of the plate 12^g are spaced from each other as clearly shown in Fig. 12 and are adjustable toward and from each other. The said plates 12^g are held in adjusted, clamped

100

position between the top plate 10^a and the bars 12^e by means of screws 12^h which extend through elongated transversely extending slots 12ⁱ in the said plates 12^g.

105

The inner edges of the plate 12^g are spaced from each other as clearly shown in Fig. 12 and are adjustable toward and from each other. The said plates 12^g are held in adjusted, clamped

110

position between the top plate 10^a and the bars 12^e by means of screws 12^h which extend through elongated transversely extending slots 12ⁱ in the said plates 12^g.

115

edge portions of the plates 12^g extend part way over the tops of the bars 11 and 12, previously referred to. As will be apparent upon reference to Fig. 12 of the drawings the opposite edges of the tape 12^g are guided by the inner opposing edges of the guide plates 12^g. In the employment of the attachment not only may the guide plates 12^g be adjusted to accommodate hook 10 and eye tape of different widths, but the bars 11 and 12 may be adjusted. These adjustments will correspond to the adjustments of the presser feet, and needles, as will be described hereinafter and are necessary in 15 order that the said attachment may cooperate in an efficient and satisfactory manner with the sewing mechanism.

Referring now to the presser foot construction, it will be noted that the presser foot bracket or holder comprises front and 20 rear plates 15 and 16 which are suitably spaced by the bosses 17 and secured together by screws such as 18. Between these two plates the angular bars 20 and 21 are located. 25 These bars are guided in their adjustments by the bosses 17. The presser feet 22 are hinged to said bars at 23. These bars 20 and 21 are provided with threaded holes 25 which are engaged by headed screws 26 which pass through horizontal slots 27 in the rear plate 16, the heads of the screws overlapping the slot walls. As will be apparent, by loosening the screws, the bars 20, 21 can be adjusted to move the respective 30 presser feet toward and away from one another. The rear plate 16 is provided with a rearward and laterally extending projection 30 which is provided with an opening 31 whereby it may be attached to the presser bar. The presser feet 22, as will be understood, are positioned above the openings 13 and the feed dogs operating therein. For the purpose of engaging the tape midway between the presser feet 22 and the said 35 openings 13 I have provided a presser foot element 32 which depends from the front plate 15, with which, in the construction here shown, it is integral.

The needle holder comprises the rod 35 50 which is provided with a crossbar 36 on its lower end. Upon this bar 36 is slidably positioned a pair of brackets 37 which are grooved on their rear faces to receive said bar as shown most clearly in Fig. 6. These 55 brackets are provided in their lower portions with upwardly extending sockets to receive the upper end of the needles 38, which are fastened in place by set screws 39. The brackets 37 are formed with longitudinal slots 40 of T-form in cross section through which pass headed screws 41 which are threaded into suitable tapped holes adjacent the opposite ends of the bar 36. By 60 loosening these screws 41 the needles can be 65 adjusted inwardly or outwardly with the ad-

justments of and in conformity with the presser feet and feed dogs.

In Figs. 7 and 8 I have shown a modified construction arranged to facilitate setting the two needles at equal distance from the median plane of the device. As here shown the bar 36 is formed with a longitudinal slot 45 in which it positioned a gage block 46 which is stepped evenly from the center to the ends along one edge as at 47. Passing freely through the bottom wall of the slot 45 and threaded into a suitable socket in the block 46 is a screw 48 which is held against axial displacement by a member 49 engaging the head thereof. By rotating this screw the block 46 can be projected varying distances from the bottom of the slot 45. The shoulders formed by the steps 47 operate as stops to limit the inward adjustments of the needle holding parts 37. The positions of the shoulders depend upon the position of the block 46 with respect to the slot 45.

Having thus described my invention what I claim as new and desire to protect by Letters Patent of the United States is as follows.

1. In a sewing machine attachment, a presser foot bracket comprising spaced front and rear plates, horizontally adjustable angular bars positioned between said plates and each projecting at one end from between said plates, and presser feet secured to the projecting ends of the said bars.

2. In a sewing machine attachment, a presser foot bracket comprising spaced front and rear plates, angular bars positioned between said plates and each projecting at one end from between said plates, said bars being adjustable toward and from each other, and presser feet secured to the projecting ends of the said bars, and screws engaged with said bars to lock them in adjusted positions.

3. In a sewing machine attachment, a presser foot bracket comprising spaced front and rear plates, angular bars positioned between said plates and each projecting at one end from between the lower edges of said plates, and presser feet hinged to the projecting ends of the said bars, and screws in engagement with said bars to lock them in adjusted position, said screws passing through horizontal slots in the rear plate.

4. In a sewing machine attachment, a presser foot bracket comprising spaced front and rear plates, angular bars positioned between said plates and each projecting at one end from between the lower edges of said plates, and presser feet hinged to the projecting ends of the said bars, and a presser member rigidly connected with the front plate, which presser member is located between the presser feet.

5. In a sewing machine attachment, a

presser foot bracket comprising spaced front and rear plates, means between said plates forming transversely extending notches, bars located between the said plates, the opposite end portions of each of said bars being arranged substantially at right angles to each other, one of the said end portions of each bar being mounted within one of said notches and being adjustable therein, and the other end portion of each bar projecting below the lower edges of said plates, presser feet secured to the projecting ends of said bars, and means for engaging said bars to lock them in adjusted positions.

15 6. In a sewing machine attachment, a

presser foot bracket comprising spaced front and rear plates, angular bars positioned between said plates and each projecting at one end from between the lower edges of said plates, said bars being horizontally adjustable, presser feet secured to the projecting ends of said bars, means for holding the said bars in adjusted positions, and devices located in proximity to said presser feet and adjustable toward and from each other for 20 guiding the work under said presser feet. 25

In testimony whereof I have affixed my signature.

ABRAHAM BEBEL.
